2,347,577

RESONANT CAVITY OSCILLATOR

Ernest G. Linder, Philadelphia, Pa., assignor to
Radio Corporation of America, a corporation of
Delaware

Original application November 30, 1938, Serial No.
243,211, now Patent No. 2,233,263, dated Febru-
ary 25, 1941. Divided and this application
October 18, 1940, Serial No. 361,707

1 Claim. (Cl. 315—5)

This application is a division of U. S. Patent 2,233,263 which issued February 25, 1941 on application Serial No. 243,211, filed November 30, 1938, for Resonant cavity oscillators which application was assigned to the same assignee as the instant application.

This invention relates to ultra high frequency oscillators and more specially to ultra high frequency resonant cavity oscillators.

The term "ultra high frequency oscillations" is generally applied to electromagnetic oscillations having a frequency of the order of 500 megacycles per second and upward. At the higher frequencies, for example, 3000 megacycles, it has been difficult to generate powerful oscillations. This difficulty has been due to the space characteristics of the thermionic tubes which are employed. The prior art devices have been known as magnetron and Barkhausen Kurz oscillators. In these oscillators, the radio frequency potentials are applied to the electrodes by means of resonant circuits.

The difficulties of generating radio frequency oscillations corresponding to a wave length of 10 centimeters will be appreciated by considering the physical size of a magnetron oscillator in which the anode electrode is a cylinder of the order of 2 millimeters radius and one centimeter length. In this arrangement, the anode is subjected to intensive heat when even low power oscillations are generated.

Thus, it is quite apparent that the space limitations of the thermionic oscillators of the prior art have prevented the generation of more than about 10 watts of ultra high frequency oscillatory energy. I propose to avoid structural limitations by employing tube elements which are not connected by resonant circuits and which do not themselves oscillate. In other words, the radio frequency potentials will not be applied to the tube elements which will further remove the restrictions of size. In place of resonant circuits, I propose to employ a cavity which will resonate to oscillations of a predetermined frequency. The cavity may have a size corresponding to a predetermined number of wave lengths. The oscillatory energy established within the cavity may be collected by an appropriately arranged conductor upon which the waves induce electro-motive forces of the desired frequency.

As used in this specification, the term "free electrons" is applied to electrons within the field and external to the conductors. The free electrons are of two types: in-phase and out-of-phase. "In-phase" electrons is the term applied

to free electrons which subtract energy. "Out-of-phase" electrons is the term designating free electrons which deliver their energy of motion.

It is one of the objects of the invention to provide means for generating ultra high frequency oscillations of greater power than has hitherto been practical. Another object of the invention is to provide means for establishing oscillations within a resonant cavity. A still further object is to arrange thermionic tube elements within a resonant cavity whereby free electrons establish resonant oscillations within the cavity. A still further object is to provide means for creating free electrons within a cavity which is adjusted to establish therein standing electric waves.

The invention will be described by referring to the accompanying drawing in which Figures 1 and 1A are schematic diagrams of one embodiment of the invention, and Figures 2 and 2A are schematic circuit diagrams of the preferred embodiment of the instant invention.

Referring to Fig. 1, within one end 1 of a hollow metallic cylinder 3 are suitably arranged on an insulator 5 a lattice-like cathode 7 and an accelerating electrode 9. The cathode is energized by a source of power 11 and the accelerating electrode is made positive with respect to the cathode by a battery 13. The end portion of the cylinder is surrounded by a solenoid 15 which is energized by a battery 17. The opposite end of the cylinder 3 includes a movable end portion 19 which is hermetically sealed to the cylinder by means of a bellows 21. The end plate is coupled to a screw 23 which is used to adjust the position of the movable end plate 19. A coupling loop 25 is inserted within the cylinder through suitable insulators.

The operation of the device is as follows: Electrons emitted by the cathode 7 proceed toward the accelerating electrode 9. Some of the electrons will reach the electrode, but most, due to the deflection of the magnetic field, will be projected past the electrode toward the walls of the cylinder 3.

Upon reaching the neighborhood of the cathode in a region roughly diametrically opposite to their place of emission, their radial motion will be reduced to zero and then reversed, and they will again be attracted towards the accelerating electrode. Thus an oscillatory motion in a radial direction will be established. An electron swarm will be formed about the electrode 9. The swarm consists of radially oscillating electrons, upon which a comparatively slow angular precession

is superimposed by the magnetic field due to the solenoid 15. The sole purpose of the angular component of motion induced by the magnetic field is to cause a large portion of the electrons to miss electrode 9 and thus execute a substantial number of oscillations about it before being collected. The angular electron motion does not contribute directly to the establishment of the electric field oscillations. These oscillations are caused by the radial component of electron motion.

The oscillating electrons in the swarm will radiate energy into the surrounding space in the form of an electro-magnetic wave, whose frequency corresponds to the frequency of their own oscillatory motion, and whose electric vector is parallel to their own direction of motion. If the cavity is of suitable dimensions, standing waves will be set up. The electric field thus established will react upon the electrons in the swarm.

Originally (i. e., before the formation of a standing wave), the electrons oscillate with a random distribution of phases. However, due to the reaction of the electric field, a grouping is caused. Some electrons will be moving in phase with the electric oscillations of the field. These will gain energy and their amplitude of motion will increase. Their orbits will thus soon penetrate beyond the cathode 7 into the space between the cathode 7 and the cavity wall. This is a field free space insofar as nonoscillating fields are concerned, and all electrons reaching it will immediately travel to the cavity wall and be collected. Thus, in-phase electrons tend to be rapidly removed from the swarm. On the other hand, electrons which oscillate 180° out of phase are constantly moving in an A. C. field which opposes their motion, and hence lose energy and remain much longer within the region adjacent the cathode. This lost energy of motion appears as energy of electromagnetic field oscillations. These electrons are eventually collected by the accelerating electrode 9.

Although, for the sake of clarity, the above discussion has been applied only to in-phase electrons and electrons 180° out of phase, it actually applies to all electrons. This follows, since all electrons may be put into one of two classes (1) those which are in phase during most of a cycle, and (2) those which are out of phase during most of a cycle. It is obvious that the grouping effect will occur for those two classes in much the same manner as for electrons in phase or out of phase during the entire cycle, as described above.

It should be understood that the magnetic field, potential of the electrodes and size of the resonant cavity should be adjusted to obtain the optimum oscillations within the cavity. The electric oscillations thus generated induce electromotive forces in the coupling loop 25 whose terminals are connected to an antenna, transmission line, or other useful load circuit.

In Figs. 2 and 2A, a partially spherical resonant cavity 83 is arranged within the spherical envelope 85. Reentrant portions are formed by a pair of inwardly extending, oppositely disposed frusto-conical members whose axes lie along a line extending through the center of the spheri-

cal envelope. Free electrons are set up within the resonant cavity by the cathode 87, control grid 89 and electrode 91. It will be observed that the electrode 91 is biased negatively with respect to the cathode 87; therefore, the electrons approaching the electrode 91 will be repelled and will reenter the cavity. The reentering out-of-phase electrons will give up energy to aid in the creation of or to strengthen the standing waves which are established as previously described. In this arrangement, the standing waves established within the cavity are partially spherical in form. No load circuit is shown, but it should be understood that the load circuit may take the form of a pickup coil, antenna or the like.

Thus the invention has been described as a resonant cavity oscillator. I am aware that G. C. Southworth, in his U. S. Patent 2,129,713, has described ultra high frequency oscillators which are positioned within a wave guide. The oscillators used by Southworth are of the conventional type. The radio frequency potentials established on the oscillator elements radiate waves which travel through the wave guide. As previously explained, my invention relates to a new form of oscillator in which the elements of the thermionic device create clouds of free electrons some of which deliver energy directly to create and maintain standing waves within a resonant cavity.

In the above-described devices, the resonant cavities have dimensions large compared to a wave length. The resonant cavity cylinders will be able to handle large cathode emission currents and very high accelerating electrode potentials. Large amounts of heat can be dissipated, since the accelerated electrons strike the external internal portion of the cylinder, and its entire surface serves to radiate the heat produced. The electrodes (cathodes and grid) are nonoscillating and thus consideration of electrode capacity and inductance play no part. These electrodes are limited in size only by geometrical consideration. It is evident that the currents, voltages and power involved are all much greater than those utilizable by any previous type of device operating at such high frequencies.

I claim as my invention:

An ultra high frequency oscillator including a resonant chamber of spherical shape having a pair of reentrant portions including apertures, at least one tubular conductive member surrounding one of said apertures and extending from said chamber into one of said reentrant portions, means for emitting free electrons, means for focusing said electrons, means for projecting said electrons through said apertures and through said chamber, means including an electrode disposed outside of said cavity but within said one of said reentrant portions thereof and within said tubular member for phasing said electrons so that out-of-phase electrons will deliver their energies to establish and maintain spherical waves within said chamber, and means for biasing said electrode negatively with respect to said electron emitting means for repelling electrons approaching said electrode so that said repelled electrons will reenter said cavity in proper phase to sustain oscillations.

ERNEST G. LINDER.
